UNITED STATES PATENT OFFICE.

GLENN J. BARRETT, OF GRAND RAPIDS, MICHIGAN, ASSIGNOR TO BARRETT ADDING MACHINE COMPANY, OF PHILADELPHIA, PENNSYLVANIA, A CORPORATION OF DELAWARE.

"PUNCTUATING DEVICE FOR ADDING-MACHINES.

1,127,953.

Specification of Letters Patent.

Patented Feb. 9, 1915.

Application filed February 4, 1913. Serial No. 746,103.

To all whom it may concern:

Be it known that I, GLENN J. BARRETT, a citizen of the United States, residing at Grand Rapids, Michigan, have invented 5 certain new and useful Improvements in Punctuating Devices for Adding-Machines, of which the following is a specification.

My invention relates to improvements in punctuating devices for adding machines 10 and it has for its objects to provide a device of this character which may be employed to ascertain the denominations of currency required to properly make up a pay roll or like list of disbursements; to provide a device 15 of such character which will automatically lock the keys of such columns of an adding machine as may be desired against depression to render the same inoperable; to provide a device of such character that 20 it will admit and will enable the division of the keyboard in such manner as may meet the operator's convenience and requirements; and also to provide a device of the character which may be readily removed 25 from position upon the machine when not in use.

Other and further objects of my invention will be hereinafter referred to in the specification or will be apparent therefrom.

30 In the accompanying drawings I have illustrated a structure showing a convenient embodiment of my invention and also illustrating the principle of operation of the same. However, it should be understood that changes in the details of construction may be made within the scope 35 of the claims without departing from my invention.

In order that my invention may be more 40 readily and clearly comprehended, reference should be had to the accompanying drawings, in which,—

Figure 1 is a plan view of an adding machine having a device embodying my invention applied thereto, such device being 45 arranged upon the machine in said figure in positions to determine the denominations of currency to the left of the decimal point; Fig. 2 is a view similar to that shown in 50 Fig. 1 but with the device embodying my invention arranged in position for determining denominations of coin to the right of the decimal point; Fig. 3 is a transverse sectional view taken on the line 3—3 of Fig.

2, the said section extending only through 55 the top plate of the casing of the adding machine; Fig. 4 is a longitudinal sectional view taken on the line 4—4 of Fig. 2, the said section extending only through the top plate of the adding machine and the said 60 view, also showing a divider embodying my invention in edge elevation, and some of the key stems of one of the columns of keys; and Fig. 5 is a perspective view of one of the devices embodying my invention.

I have illustrated my invention in connection with a form of adding machine illustrated in United States Letters Patent No. 976,336, issued November 22nd, 1910, 70 but it will be understood that the form of adding machine to which my invention is applied is immaterial.

In the drawings,—1 designates the casing of an adding machine and 2 designates 75 an operating handle of known construction. The said machine is provided as usual with a number of columns of key stems which extend longitudinally of the machine. The device which constitutes a denominating 80 divider consists of a main or body portion 3 having ears 4 and 5 which project laterally from its upper or rear end portion. The purpose of these ears is to prevent the device from sliding forwardly during the 85 operation of the machine. The said device is provided with locking ears 6 for the purpose of preventing the depression of the keys which are not to be used in determining currency denominations. A numeral or 90 other sign designated by the reference numeral 8 is placed upon the device to correspond with any special denomination of money, as, for instance, one dollar bills, two dollar bills, five dollar bills, etc., or five 95 cents, ten cents, twenty cents, etc. The lower end of each device designated by the reference numeral 10 constitutes an indicator for indicating the dial of units denomination in the column coöperating with the 100 key stems opposite the numeral or other symbol designated by the reference number 8.

11 designates a pointer alining with the column of key stems in which additions are 105 to be made when using my device. It will be observed upon reference to the drawings, particularly Figs. 3 and 4, that the locking

ears or projections 6 when the device is in operative position are situated directly underneath the heads 12 of the key stems so as to prevent operation of such key stems 5 as may have their heads so situated with respect to such ears or projections.

The use of devices embodying my invention may be readily understood by reference to Figs. 1 and 2 of the drawings. I 10 shall first describe the operation of the same in connection with Fig. 1 in which devices are arranged for determining the denominations and number of each required for bills or amounts to the left of the decimal point. It will be seen that two columns 15 are allowed at the extreme right hand of the key-board for the one dollar bills; that three columns are allowed for the five dollar bills; that three columns are allowed 20 for the ten dollar bills; and that two columns are allowed for bills of the denomination of twenty dollars.

In Fig. 2 I have shown my device arranged for ascertaining and determining 25 the number of the different denominations of coins required. I have allowed two columns each for cents, nickels, dimes, quarters, and half dollars.

To better understand the operation of my 30 device it will be supposed that an operator is desirous of ascertaining the number of each of various denominations of currency necessary to make up the following amounts,—

35	\$36.75
	25.45
	24.49
	12.36
	9.54
40	8.91
	4.98
	\$122.48

45 Considering first the amounts of the items to the left of the decimal points in order, we find that to make up the sum of thirty-six dollars, one twenty, one ten, one five, and one one dollar bill are required. Accordingly in each column covering the above 50 denominations which are opposite the numerals 20, 10, 5 and 1, a key stem having a button or head with the numeral 1 thereon is depressed because there is but one each 55 of the various denominations making up the sum of \$36.00 required. The machine shown in the drawings being a key set handle operated adding machine, the handle is drawn forward after the several keys 60 have been set and the dials coöperating with the respective columns record or indicate the number of each denomination which is required. The next item, twenty-five dollars, will require one twenty and one five 65 dollar bill. Accordingly, a "1" button is

depressed in the columns corresponding to those denominations on the denomination dividers and the handle operated as before. The item twenty-four dollars is made up of one twenty dollar bill and four ones, 70 and requires the depression of a "1" button in the column opposite, or in alinement with, the numeral 20, and a "4" button in the column opposite, or in alinement with, the numeral 1 on the device at the right 75 hand side of Fig. 1. The item of twelve dollars comprising a ten dollar bill and two one dollar bills, requires the depression of a "1" button in the "10" column and a "2" button in the "1" column. The item of nine 80 dollars comprising a five dollar bill and four ones, requires the depression of a "1" button in the "5" column and a "4" button in the "1" column. The item of eight dollars comprising a five dollar bill and three 85 ones, requires the depression of a "1" button in the "5" column and a "3" button in the "1" column. The item of four dollars which is the last one given in the problem to be solved, requires the depression of a 90 "4" button in the "1" column.

In Fig. 1, I have shown the result on the dials after completing the foregoing operation and it will be seen that the various denominations necessary to make up the 95 amounts of the several items to the left of the decimal points in the problem solved would require three twenty, two ten, four five, and eighteen one dollar bills.

After having determined as above the 100 number of bills of each denomination which will be required, it will be next in order to ascertain the number of coins of each denomination which will be required to make up the amounts upon the opposite or right 105 hand side of the decimal point. To do this the operator should first clear the adding machine, that is, restore the dials to the "zero" point, and arrange the denominating dividers in the manner shown in Fig. 2. 110 He will then proceed exactly as when determining the number of each denomination upon the other or left hand side of the decimal points. After having carried this operation through it will be found that 115 to make up these several items upon the right hand side of the decimal points, four fifty-cent pieces, six quarters, eight dimes, one nickel and thirteen one-cent pieces will be required. These amounts will be seen 120 upon the respective dials in Fig. 2 of the drawings. The operator may then check up these amounts by taking first the denominations to the left of the decimal points and adding the values they represent, for instance, three twenty-dollar bills, two tens, four fives, and eighteen ones, which make a total of one hundred and eighteen dollars. In the same way by adding what is represented by the dials in Fig. 2 he will find the 125 130

total to be \$4.48. Then by adding these sums together he will secure a total of one hundred twenty-two dollars and forty-eight cents.

5 I claim:—

1. In combination with an adding machine having columns of finger keys, a removable key-locking punctuating device, comprising an indicator, pointer, locating 10 ears, a denominating numeral, and locking ears.
2. In combination with an adding machine having columns of depressible finger keys and accumulating dials, a removable 15 denominating punctuating device, having an indicator to coöperate with the dials, a denominating numeral and pointer in proximity to the operative column of said adding machine, and locking ears to engage the in- 20 operative finger keys of said adding machine.
3. In combination with an adding machine having columns of depressible finger keys and accumulating dials, a removable 25 punctuating denominating device comprising an indicator, a denominating numeral in proximity to the operative columns of finger keys, and means for retaining said denominating device in position during the 30 operation of the said adding machine.
4. In combination with an adding machine, having columns of depressible finger keys, a denominating punctuating device provided with means for preventing the de- 35 pression of a selected row of keys with which said device is associated and the said device being provided with means coöoperating with one or more of the said finger keys to retain the said device in operative position.
- 40 5. In combination with an adding machine, having columns of depressible finger keys, a denominating punctuating device provided with means for preventing de- 45 pression of a selected row of keys with which said device is associated and the said device being provided with ears for contacting with one or more of the said finger keys to retain the said device in operative position.
- 50 6. In combination with an adding machine, having columns of depressible finger keys, a denominating device adapted to be associated with said keys and having means thereon for preventing depression of a se-

lected column of keys with which said device is associated.

7. In combination with an adding machine, having parallel columns of depressible finger keys, a denominating device consisting of a member adapted to be situated between any two parallel columns, the said member having means upon one side thereof to prevent depression of the keys situated at that side of the said member and the said member being provided with means whereby it is removably retained in operative position.

8. In combination with an adding machine, having parallel columns of depressible finger keys, a denominating device adapted to be positioned between any two 70 columns, the said device consisting of a member having indicating means thereon and means upon one side thereof for preventing depression of the finger keys upon the same side of the said member and being 75 provided also with means for contacting with one or more of the said finger keys whereby the said device is retained in operative position.

9. As an article of manufacture, a punctuating device for computing machines consisting of a member having means thereon for preventing the depression of a selected number of the finger keys of such machine and also having means thereon for retaining the said device in position upon the machine when it is placed in operative position thereon.

10. As an article of manufacture, a punctuating device for computing machines consisting of a plate-like member having indicating means thereon and being provided with means for preventing depression of a selected number of keys in any selected row of keys upon the said machine, and the said 95 device also being provided with means for retaining the said device in operative position upon the said machine.

In testimony that I claim the foregoing as my invention, I have hereunto signed my 100 name this 31st day of January, A. D. 1913.

GLENN J. BARRETT.

In the presence of—

EVERETT E. THAYER,
FRANK W. MOSHER.
